UNITED STATES PATENT OFFICE.

WARREN E. GLASPEY, OF BRIDGETON, NEW JERSEY, ASSIGNOR TO SPRING STOPPER COMPANY, OF NEW YORK, N. Y., A CORPORATION OF DELAWARE

MACHINE FOR MAKING BOTTLES, ETC.

Application filed May 29, 1922. Serial No. 504,596.

To all whom it may concern:

Be it known that I, WARREN E. GLASPEY, a citizen of the United States, residing at Bridgeton, in the county of Cumberland and State of New Jersey, have invented a new and useful Improvement in Machines for Making Bottles, Etc., of which the following is a specification.

This invention relates particularly to machines for making bottles, or similar containers, which are provided within the mouth-portion with an internal screw thread; and the primary object of the invention is to provide an improved machine for the purpose indicated, which is capable of large output, which reduces wastage to a minimum, and which is economical in operation.

The invention is illustrated, in its preferred embodiment, in the accompanying drawings, in which—

Figure 1 represents a broken plan view of a bottle-making machine embodying the invention; Fig. 2, a broken vertical sectional view showing a friction clutch device with which the mandrel-pinions are equipped; Fig. 3, a broken elevational view of the improved machine; Fig. 4, a broken vertical sectional view taken at the bubble-blowing station; Fig. 5, a broken plan sectional view illustrating the manner in which the molds are mounted on the intermittently-actuated rotary table; and Fig. 6, a vertical sectional view of the mechanism shown in Fig. 5.

It may be stated preliminarily that a bottle-making machine of the general type illustrated is known, such machine involving the use of a rotary mold-carrier having invertible molds mounted on the carrier. The present invention relates particularly to the provision of means in connection with such machine whereby bottles having internally threaded mouth portions may be produced by means of such a machine. Certain of the features of improvement are adapted, however, for use in connection with bottle-making machines generally.

Also, it may be stated preliminarily that in the construction herein illustrated the rotary mold-carrier is equipped with revoluble mold-supports which serve to invert the molds and then right them as the molds are carried in their orbit; a pinion-equipped

threaded mandrel is carried with each mold; and a pair of yieldingly-mounted curved racks are employed for raising and lowering the mandrels, seriatim, one of said racks being concave and the other one being convex, the racks being located on opposite sides of the path of the pinions with which the mandrels are equipped. At the intermediate station shown in Fig. 1, the glass-charging operation is performed after the mandrel has been elevated; and at the next station the bubble-blowing operation is performed after the mandrel has been lowered. At the intermediate station a blow-head is employed to force the glass down into the lower portion of the mold so that it will form properly about the threaded tip of the mandrel in the neck portion of the mold. Each mandrel has a threaded stem which works through a nut which is mounted in coaxial alignment with the mold.

It may be added at this point that the bottle-blanks or parisons, are formed in the machine illustrated in the accompanying drawings; that the molds are, in the operation of the machine, inverted and opened and the parisons or bottle-blanks are transferred to a blowing machine; and that the final operation of blowing the bottles is performed in the machine last referred to, no illustration of such machine being required for the purpose of the description of the present invention.

In the embodiment of the invention illustrated, A represents the base of a frame from which rises a stationary shaft or column A'; B, a rotary mold-carrier having revolubly mounted thereon a series of mold-supports B', upon which are mounted molds B'; B², a large gear through the medium of which the mold-carrier B is rotated, so that the molds will be carried in an annular path or orbit; C and C' stationary cams which serve to close and open the molds; D, a stationary bevel-gear segment which serves to rotate the mold supports and invert and then right the molds as they are carried through their orbit; E, a threaded tubular mandrel associated with each mold, each mandrel being equipped at its projecting lower end with a gear-element or pinion E'; F, a yieldingly mounted concave rack which serves to elevate the mandrels, in turn, as

they pass to glass-charging station; F', a yieldingly-mounted convex rack which serves to lower the mandrels, in turn, as they are carried from the glass-charging station to 5 the bubble-blowing station; G, a bubble blow-head which is mounted beneath the path of the molds at the left hand station shown in Fig. 1; and H, a blow-head located above the path of the molds at the 10 glass-charging station.

The frame which comprises the base A and column A' may be of any suitable construction. The fixed center column A' serves as an axis about which the mold-table B, 15 actuated by the gear E^a, turns; and the column A' serves also to support certain mechanisms, including the blow-head which is employed for blowing the glass down into the mold so that it will form properly about 20 the tip of the mandrel in the neck portion of the mold. The blow-head H employed for this purpose is of the usual construction, and operates in the usual manner.

The mold-table is given an intermittent 25 or step-by-step movement in any desired manner. The mold-carrying means comprises the table B and the series of mold-supports B' arranged thereon. Each mold-support comprises a hollow trunnion or 30 gudgeon 1 and a disk or face-plate 1^a formed integrally therewith. The hollow trunnion 1 is journaled in a divided bearing-box 2 which is securely fastened to the table B.

Each mold B^a comprises a pair of main 35 mold sections 3 and a pair of ring-mold sections 3^a. These sections meet in a vertical plane and are provided with arms 3^b and 3^c, respectively, which are connected at their inner ends with a pivot 4 carried by 40 lugs 4^a which project from the face-plate 1^a. Thus, the mold sections are capable of separating at a plane containing the axis of the mold.

The threaded mandrel or plunger E, associated 45 with each mold, works in a nut 5 which is rigidly secured to a bracket 5^a, the bracket 5^a being rigidly mounted on the face-plate of the mold-support B'. The bracket 5^a comprises a tubular member 5^b carried by a shank 5^c; and a pair of strong studs or bolts 5^d which project from the face-plate of the mold-support B'. The shank 5^c of the bracket is equipped with loops or rings 5^e which are mounted on the laterally projecting 50 studs 5^d. The tubular portion 5^b of the bracket is thus staunchly supported on the studs 5^d and may be adjusted thereon, if desired. Any suitable securing means (not shown) may be employed. The tubular portion 5^b of the bracket is located directly below the mold and is provided at its upper portion with a peripheral flange 5^f which interlocks with flanges with which the ring-sections 3^a of the mold are provided. The nut 5 55 has a portion which projects into the tubular

member 5^b and has a flange 5^g which is secured by bolts (not shown) to the tubular member 5^b.

Above the nut 5 is a space or chamber 6. The mandrel E extends through this chamber. It has a tip portion 7 which is provided with a thread 7^a which serves to form a thread within the mouth of the bottle. The tip portion of the mandrel has a reduced tubular shank 7^b which is fitted securely 75 within the hollow shaft which forms the main shank 7^c of the mandrel. The shank 7^c is externally threaded and engages the nut 5. The pitch of the thread on the shank 7^c corresponds with the pitch of the thread 7^a at the tip of the mandrel. The hollow mandrel tip 7 is provided with laterally-opening orifices 7^d adapted to permit air to pass into the chamber 6 during the bubble-blowing operation. The upper portion of 80 the threaded shank 7^c is provided with a lateral stud 8 which is adapted to engage an inwardly-projecting stud 9 which extends into the upper portion of the chamber 6, and thus limit the upward movement of the 85 mandrel. The stud 8 is also adapted to engage a stud 10 which projects upwardly from the nut 5, and thus limit the downward movement of the mandrel.

The pinion E' of each mandrel is frictionally mounted on the lower end of the mandrel-shank 7^c, as will be clearly understood from Fig. 2. The purpose is to permit the pinion to slip or turn with relation to the mandrel after the mandrel has been 100 raised or lowered by the rack. In the illustration given, the shank 7^c of each mandrel is provided with a reduced lower end portion 11 encircled by sections 11^a of a cone which engage the interior conical surface 11^b 105 of the pinion E'. The cone-sections 11^a are yieldingly held in gripping position by a coil spring 11^c which is interposed between the cone sections and a nut 11^d which is mounted on the reduced end 11 of the shank 110 of the mandrel. In practice, the racks are made somewhat longer than would be required to elevate or lower the mandrels, and provision for slippage of the pinions, that is, rotation of the pinions without further movement of the mandrels, is made. The friction device shown answers the purpose admirably, but any other suitable connection 115 may be employed.

The racks are preferably mounted on yieldingly-held bell-crank members. The purpose is to permit a sufficient yielding of the rack to insure the pinion coming properly into mesh with the rack, thus avoiding breakage as might otherwise occur 120 in case the end of a tooth of a pinion should strike the end of a tooth of the gear-segment or rack.

Thus the internally-toothed gear segment F is carried by a pair of bell-crank levers 130

12. These bell-crank members have arms 12^a which are pivotally connected with the rack at points 12^b. The bell-crank members 12 further have vertical pivot portions 12^c journaled in the upper portion of a bracket 13, and have lower arms 12^d with whose extremities are pivotally connected bolts 12^e. These bolts pass freely through lugs 14 carried by the standard or bracket 13, and are equipped with nuts 12^f which serve to adjust the tension of springs 15 which are confined between the lugs 14 and the arms 12^d. Thus the springs 15 serve to hold the rack F yieldingly in the position shown in Fig. 1.

15. In a similar manner, bell-crank members 16, equipped with springs 16^a, serve to hold the rack F' yieldingly in the position shown in Fig. 1. The bell-crank members 16 are mounted on a bracket or standard 17 carried by the base of the frame.

20. As will be understood from Figs. 1, 5 and 6, the mold sections are opened and closed through the medium of a plunger 18 which extends through the hollow trunnion 1 of the mold support, the other end of the plunger being connected, by links 19, with the mold sections. Each plunger 18 is equipped at its inner or rear end with a cam roller 18^a; and 25 the movements of the plunger are controlled by the cams C and C' shown in Fig. 1.

25. On the hollow trunnion 1 of each mold support is secured a bevel gear 20. These bevel gears are adapted to travel on the bevel-rack D and revolve the mold-supports on their axes during the rotation of the mold-table B. The rack D is a stationary rack, supported in any suitable manner (details not shown). The molds may be maintained in their normal upright position by any suitable expedient (not shown). If desired, frictional contact between the trunnion 1 of the mold-support and the sectional bearing-box may be such as to cause the bearing-box to grip the trunnion of the mold-support sufficiently to maintain the mold in its upright position during the passage of the mold from one station to another. Any suitable locking devices may be employed for releasably locking the molds in upright position, so that they will be properly maintained in such position during their travel in the upright position.

30. The chamber 6 shown in Fig. 4 communicates through a central passage 6^a with the neck portion of the mold cavity. Thus when the mandrel is retracted air may pass from the bubble-blower into the cavity in the glass and blow the glass to complete parison form.

35. The bubble blow-head G shown in Fig. 4 comprises a pipe 21 equipped with a vertical head 22 on which is swiveled a vertical tip 23. A depending stem 24 carries the device G, this stem being equipped with a piston 25 working in a cylinder 26. The

blow-head G is elevated by pneumatic pressure. The blow-head rises above the position shown in Fig. 4 and is then depressed by the mandrel, the tip portion 23 of the device rotating with the mandrel. This action is permitted by a ball bearing 27. The pneumatic pressure which raises the piston 25 is sufficiently light to enable the blow-head to be depressed by the mandrel, as the mandrel descends, until the stud 8 engages 70 the stop 10. The portion 23 of the device G is provided with a bevel tip 23^a which is adapted to engage a conical recess 28 with which the tubular mandrel shank is provided at its lower end as shown in Fig. 2.

30. The operation of the improved machine may be stated briefly as follows:

35. The mold-table B is given an intermittent movement of rotation in the usual manner, the rotation being effected through the medium of the large gear B^a. As the molds are carried past the concave rack F, the mandrel pinions travel along the rack and cause the mandrels to be elevated. Thus, the mandrels occupy the elevated position when they reach the glass-charging station, which is the intermediate station shown in Fig. 1. At this point, the operation of introducing the "metal," or molten glass, is performed, a funnel I being employed, if desired to facilitate this operation. The glass is severed by means of a shear J shown broken in Fig. 3. In practice, a suitable automatic charging device is employed. After the requisite amount of glass is introduced, the blow-head H descends, and air pressure is exerted upon the glass in the mold, thus forcing the metal to form properly about the mandrel in the neck portion of the mold. As the mold is carried from the charging station to the bubble-blowing station, the mandrel-gear is engaged by the yielding rack F', and this rack, being located on the inner side of the path of the mandrel-gears, serves to unscrew the mandrels or lower them. The lowering action occurs until the stud 8 engages the lower stop 10 shown in Fig. 4, after which the mandrel-gear turns idly on the mandrel. Before the mandrel is completely lowered, however, the bubble-blower G shown in Fig. 4 rises to meet the mandrel, but is forced back again against the air pressure in the cylinder 26 during the final portion of the lowering movement of the mandrel. When the mandrel is completely lowered, the air entering the chamber 6 passes through the central passage 6^a into the cavity previously formed in the glass by the mandrel tip, and the glass is blown into the form of a complete parison. After the parison has been blown, the mold carries it from the bubble-blowing station. The mold in the course of its travel is rotated about the horizontal trun-

nion of the mold support to invert the parison. Also, the mold is opened, and the parison is transferred to the blowing machine, where the operation of blowing the 5 complete bottle is performed.

The improved machine operates in the same automatic manner as do machines of this type employed for making bottles having plain, or unthreaded interior mouth 10 surfaces; and the improved machine is capable of the usual large output of an automatic machine of this type. Thus, bottles of merchantable character can be produced economically and in large quantities, such 15 bottles being provided in their mouth portions with internal threads.

The features of providing the gear-segments, or racks, with yielding mountings and providing for slippage between the 20 mandrel and the mandrel gear are of great practical advantage. These features insure the proper meshing of the mandrel-gear with the rack, prevent jamming, and consequent breakage, and make it unnecessary to 25 employ great accuracy in the racks as to length and number of teeth, care being taken to insure sufficient turning of the mandrels, however. While the improved devices 30 are shown applied to a machine equipped with invertible molds, the invention is not limited to use with the invertible mold type of machine.

The foregoing detailed description has been given for clearness of understanding 35 only and no unnecessary limitations should be understood therefrom, it being the intent to claim the invention as fully as possible in view of the prior art.

What I regard as new, and desire to secure by Letters Patent, is:

1. In a machine of the character set forth, the combination of a mold-carrier, a series 45 of molds carried thereby, a blow-head located above the path of and co-operating with said molds, in turn, nuts carried with said molds, tubular threaded mandrels working through said nuts and equipped at their lower ends with gears, a bubble blow-head located beneath the path of the molds 50 and cooperating with the tubular mandrels, in turn, and racks mounted on opposite sides of the path of said gears, one of said racks serving to elevate the mandrels, in turn, and the other serving to lower the mandrels, in 55 turn.

2. In a machine of the character set forth, the combination of a mold-carrier, a series 60 of molds carried thereby, nuts carried with said molds, threaded mandrels working through said nuts, frictionally-held gears mounted on the lower ends of the mandrels, and racks mounted on opposite sides of the path of said gears, one of said racks being adapted to turn the gears in a direction to 65 elevate the mandrels and the other of said

racks being adapted to turn the gears in a direction to lower the mandrels.

3. In a machine of the character set forth, the combination of a rotary mold-table, a series of molds carried thereby, nuts carried 70 with said molds, threaded mandrels working through said nuts and equipped at their lower ends with mandrel-rotating gears which are capable of slippage, stops serving to limit the upward and downward movements of the mandrels, and racks mounted on opposite sides of the path of said gears, one of said racks serving to turn the gears in a direction to elevate the mandrels and the other of said racks serving to rotate the 75 gears in a direction to lower the mandrels.

4. In a machine of the character set forth, the combination of a mold-carrier, a series of molds carried thereby, nuts carried with 80 said molds, threaded mandrels working through said nuts and equipped at their lower ends with gears, and yieldingly-mounted racks disposed on opposite sides of the path of said gears, one of said racks serving to rotate the gears in a direction to 85 elevate the mandrels and the other of said racks serving to rotate the gears in a direction to lower the mandrels.

5. In a machine of the character set forth, the combination with a mold-carrier and a series of molds carried thereby, of a mandrel for each mold having screw connection with the mold-carrier and provided with a threaded extremity adapted to project into the mold cavity, a gear-element on each mandrel, and yieldingly-mounted racks disposed on opposite sides of the path of the gear-elements, one of said racks being mounted in advance of the glass-charging station and the other being mounted between the glass-charging station and the bubble-blowing 90 station.

6. In a machine of the character set forth, the combination with a mold-carrier and a series of molds carried thereby, of a mandrel for each mold having screw connection with the mold-carrier and provided with a threaded extremity adapted to project into the mold-cavity, a gear-element on each mandrel, a concave rack located in advance 100 of the glass-charging station and serving to engage the gears in turn and elevate the mandrels, and a convex rack mounted on the other side of the path of the gears between the glass-charging station and the bubble-blowing 105 station and serving to engage the gears in turn and lower the mandrels, and a bubble blow-head adapted to supply compressed air to the lower portion of each mold after the lowering of the mandrel 110 thereof.

7. In a machine of the character set forth, the combination with a mold-carrier and a series of molds carried thereby, of a mandrel for each mold having screw connection 115

with the mold-carrier and provided with a threaded extremity adapted to project into the mold cavity, a gear-element on each mandrel, a rack adapted to engage the mandrel-gears, in turn, and spring-held levers carrying said rack.

8. In a machine of the character set forth, the combination with a mold-carrier and a series of molds carried thereby, of a mandrel for each mold having screw connection with the mold-carrier and provided with a threaded extremity adapted to project into the mold cavity, a gear-element on each mandrel, a rack adapted to engage the mandrel-gears, in turn, a pair of bell-crank levers carrying said rack and springs engaging said bell-crank levers and yieldingly holding the rack normally in position to mesh with the gears as they are brought into engagement therewith.

9. In a machine of the character set forth, the combination of a mold-carrier adapted to carry molds in an orbital path, a series of invertible molds mounted on said carrier, means for inverting and righting the molds, a nut mounted in alignment with and carried with each mold, a mandrel for each mold, having a threaded tip adapted to extend into the mold cavity and having a threaded shank engaging the corresponding nut, a mandrel-gear mounted on the projecting end of each mandrel, and inner and outer racks located one in advance of the glass-charging station and one between the glass-charging station and the blowing station, said racks being adapted to engage, in turn, the mandrel-gears.

10. In a machine of the character set forth, the combination of a mold-carrier adapted to carry molds in an orbital path, a series of invertible molds mounted on said carrier, means for inverting and righting the molds, a nut mounted in alignment with and carried with each mold, a mandrel for each mold, having a threaded tip adapted to extend into the mold cavity and having a threaded shank engaging the corresponding nut, a mandrel-gear mounted on the projecting end of each mandrel, the connections between the mandrel-gear and the mandrel being such as to permit slippage, stops limiting the elevation and depression of the mandrels, a rack located in advance of the glass-charging station and adapted to engage the mandrel-gears, in turn, and elevate the mandrels, and a rack located between the charging station and the blowing station and serving to engage the mandrel-gears, in turn, and lower the mandrels.

11. In a machine of the character set forth, the combination of a rotary mold-carrier, a series of mold supports equipped with trunnions journaled in said carrier, means for inverting and righting the molds, molds mounted on said mold supports, means

for opening and closing said molds, a nut mounted on each mold support, a threaded mandrel working through each nut and having its lower end equipped with a gear, a rack serving to rotate the mandrel-gears and thereby elevate the mandrels seriatim, a blow-head serving to force the glass, after the charging operation, toward the lower portion of the mold, and a rack serving to engage the mandrel-gears and lower the mandrels seriatim after the operation of said blow-head.

12. In a machine of the character set forth, the combination of a mold-carrier and a series of molds carried thereby, of a mandrel for each mold having screw connection with the mold-carrier and provided with a threaded extremity adapted to project into the mold cavity, a gear-element on each mandrel, a shiftably-mounted yieldingly-held rack adapted to be engaged by the gear-elements of the mandrels, in turn, and serving to elevate the mandrels, and a shiftably-mounted, yieldingly-held rack adapted to be engaged by the gear-elements of the mandrels, in turn, and serving to lower the mandrels, one of said racks being located outside the path of said gear-elements and the other of said racks being located inside the path of said gear-elements.

13. In a machine of the character set forth, the combination of a rotary mold-table, a series of molds carried thereby, nuts carried with said molds, threaded tubular mandrels working through said nuts and equipped at their lower ends with mandrel rotating gears which are capable of slippage with respect to the mandrels, stops serving to limit the upward and downward movements of the mandrels, racks mounted on opposite sides of the path of said gears, one of said racks serving to turn the gears in a direction to elevate the mandrels and the other of said racks serving to rotate said mandrels in a direction to lower said mandrels, a blow-head located above the path of the molds and adapted to co-act therewith, and a bubble blow-head located below the path of said tubular mandrels and adapted to supply compressed air therethrough.

14. In a machine of the character set forth, the combination with a mold-carrier and a series of molds carried thereby, of a mandrel for each mold having screw connection with the mold-carrier and provided with a threaded extremity adapted to project into the mold cavity, a gear-element on each mandrel, a blow-head disposed above the path of said molds and adapted to co-act therewith, a bubble blow-head disposed beneath the path of said tubular mandrels and adapted to co-act therewith, and yieldingly mounted racks disposed on opposite sides of the path of the gear-elements, one of said racks being mounted in advance of

the glass charging station and the other being mounted between the glass charging station and the bubble-blowing station.

15. In a machine of the character set forth, the combination of a rotary mold-carrier, a series of mold supports equipped with trunnions journaled in said carrier, means for inverting and righting the molds, molds mounted on said mold supports, 10 means for opening and closing said molds, a nut mounted on each mold support, a threaded mandrel working through each nut and having its lower end equipped with a gear, a rack serving to rotate the mandrel-gears 15 and thereby elevate the mandrels seriatim, a blow-head disposed above the path of said molds and serving to force the glass, after the charging operation, toward the lower portion of the mold, a rack serving to 20 engage the mandrel gears and lower the

mandrels seriatim after the operation of said blow-head, and a bubble blow-head disposed below the path of and co-operating with said tubular mandrels.

16. In a machine of the character set 25 forth, the combination of a mold-carrier, a series of molds carried thereby, nuts carried with said molds, threaded mandrels working through said nuts, frictionally-held gears mounted on the lower ends of the 30 mandrels, yieldingly-mounted racks disposed on opposite sides of the path of said gears, one of said racks being adapted to turn the gears in a direction to elevate the mandrels and the other of said racks being 35 adapted to turn the gears in the direction to lower the mandrels, and stops serving to limit the raising and lowering of the mandrels.

WARREN E. GLASPEY.
